UNITED STATES PATENT OFFICE.

JACOB MARCUS AND JOHN F. BERGEN, OF BROOKLYN, NEW YORK.

TROUSERS-WAISTBAND.

1,351,257.

Specification of Letters Patent. Patented Aug. 31, 1920.

Application filed February 28, 1920. Serial No. 362,170.

To all whom it may concern:

Be it known that we, JACOB MARCUS and JOHN F. BERGEN, both citizens of Republic of Poland, residing at Brooklyn, county of New York, State of New York, have invented certain new and useful Improvements in Trousers-Waistbands, of which the following is a specification.

This invention relates to improvements in trousers-waistbands, pertaining more particularly to the production of such as an article of manufacture of such form as to permit its bodily attachment to the trousers with a minimum amount of careful attention.

The invention is particularly related to that type of waistband formed of two pieces of material, namely a stiffener element and a liner element and such as that disclosed by our former U. S. Patent No. 1,321,536 issued November 11th, 1919.

Heretofore it has been the general practice to produce the waistbands of trousers from a multiplicity of elements, each formed from a strip of material of the desired length and width, these being generally produced by the tailor and assembled by him when forming the waistband. As will be understood, the cutting of these elements into strip form necessarily produces a raw edge effect at the opposite edges of the strip, and this forms one reason for the requirement of the binder or binders and the particular folding required to hide these raw edges with their possibility of fraying.

The object of the present invention is designed to overcome these difficulties by (a) producing a formation in which the raw edge conditions are reduced to a minimum and the strength increased, and (b) providing a composite structure capable of production as a separate article of manufacture which provides the complete inner formation of the band when properly attached to the trousers material, the structure being of a type which can be produced in a simple and efficient manner and sold as such for use as desired by the tailor who is not required to provide the careful detailed attention to the assembly, the structure itself meeting this particular problem.

To these and other ends, the nature of which will be readily understood, said invention consists in the improved construction and combination of parts, hereinafter fully described, illustrated in the accom-

panying drawings, and more particularly pointed out in the appended claim.

In the accompanying drawings, in which similar reference characters indicate similar parts in each of the views—

Figure 1 is a perspective view of a part of a trousers flap showing the invention applied thereto.

Fig. 2 is a perspective view of a portion of the composite structure forming the article of manufacture, and

Fig. 3 is a detail sectional view showing the structure applied.

The composite structure is shown in Fig. 2 and comprises a stiffener element 6 and a liner element 7, these being assembled to produce the structure required for the inner formation of the waistband. As will be seen, the stiffener is of the usual strip-like formation and its lower edge 8 is turned upwardly and inwardly, toward the inner face of the liner element, thus producing a strong multiply formation which is adapted to be stitched to the trousers material. This step also conceals the raw edge of the stiffener and thus prevents it from fraying or unravelling.

The liner 7 is also of strip type and can, like the stiffener, be produced by standard methods so that the widths of the two elements do not vary throughout their lengths, and such widths can be maintained standard to size. The liner is first manipulated to provide a longitudinal fold 9 the opposite walls of which are of substantially equal width and are arranged to extend below the lower edge of the stiffener so as to provide a curtain 10. A second longitudinal or return fold 11 is next provided upon the inner wall or ply of the initial fold, of the liner, after which the five plies thus produced, by the manipulation of both the stiffener and liner elements, are stitched together by a single line of stitches 12 producing the structure of Fig. 2.

When the composite structure is to be applied, the free longitudinal edge of the stiffener is placed at the proper point on the inner side of the trousers material 13, as for instance along the upper edge as shown in Fig. 3, and the structure of Fig. 2 laid on the inner face of the trousers material, the inner ply of the stiffener being in contact with the material, as shown in Fig. 3; the free portion of the liner is then turned up to the full line position of Fig.

3 and secured in position, a simple form being to close the upper edges of the trousers material, stiffener and liner; by a binder 14. The curtain 10 is next turned back and 5 a line of stitches 15 is then run through the two plies of the stiffener near the lower edge thereof, thus the structure is fastened at both edges and cannot work up above the margin of the waistband. Inasmuch as 10 the stiffener element is of multiply formation along the stitching line 15 increased strength is provided at such line. This is important in a structure of this kind since it permits the use of relatively thin and 15 cheap fabric for use as the stiffener material. After the stitches 15 have been applied the curtain is then returned to its normal position thus rendering the lower portion 20 of the stiffener that is secured to the trousers material invisible and giving the trousers a very neat, finished and attractive appearance.

While we have herein disclosed a preferred embodiment of our invention, and 25 disclosed a way in which it may be employed, it will be readily understood that changes and modifications therein may be found desirable or necessary in meeting the various exigencies of use, and we desire to

be understood as reserving the right to 30 make any and all such changes or modifications therein as may be found necessary or essential in so far as the same may fall within the spirit and scope of the invention, as expressed in the accompanying claim 35 when broadly construed.

Having thus described our invention, what we claim as new is:—

As a new article of commerce, a unitary 40 waistband structure for trousers comprising a stiffener element and a liner element, said stiffener element being folded to provide a multiply formation along one of its longitudinal edges and said liner element being folded along one of its longitudinal edges 45 to provide a skirt in overlying relation to said folded edge of the stiffener, said stiffener and liner elements being jointed together by a line of stitches extending through the plies of their folded portions 50 and the said stitches being adapted to be concealed by a ply of the liner element when in applied position.

In testimony whereof, we have signed our names to this specification this 26th day 55 of February 1920.

JACOB MARCUS.
JOHN F. BERGEN.
